UNITED STATES PATENT OFFICE.

WILLIAM L. CHAPMAN, OF NEW YORK, N. Y., ASSIGNOR TO MERRITT & CHAPMAN DERRICK & WRECKING COMPANY, OF NEW YORK, N. Y., A CORPORATION OF WEST VIRGINIA.

PIPE-LAYING APPARATUS.

1,393,943.

Specification of Letters Patent.

Patented Oct. 18, 1921.

Application filed September 13, 1919. Serial No. 323,496.

To all whom it may concern:

Be it known that I, WILLIAM L. CHAPMAN, a citizen of the United States, and a resident of the borough of Manhattan, 5 county of New York, and State of New York, have invented an Improvement in Pipe-Laying Apparatus, of which the following is a specification.

My invention relates to means for laying 10 submarine pipe and the principal object of my invention is to provide mechanism of this type which will operate more effectively over uneven bottoms. Other objects of my invention will be apparent from a consideration of the following specification in which I have described for illustrative purposes one form which my invention may assume.

In the drawings accompanying this specification and forming a part thereof:

Figure 1 represents a general assembly of my improved pipe skid;

Fig. 2 represents a bottom plan section, 25 illustrating in detail the joint between the skid sections B and C;

Fig. 3 is a side elevation of the joint disclosed in Fig. 2;

Fig. 4 is a section on the line 4—4 of Fig. 3;

Fig. 5 is a section on the line 5—5 of Fig. 1;

Fig. 6 is a section on the line 6—6 of Fig. 1; and

Fig. 7 is a section on the line 7—7 of Fig. 1.

In Fig. 1 is illustrated in a general way a pipe-laying scow 11 provided with a suitable pipe-handling apparatus such as the derrick 12 and tackle 13. Suitable means, 40 such as the drum mechanism 14, are provided on the scow for supporting the skid section D and controlling both its elevation and its angular position. The lower and rear end of the skid section D rests upon the bottom. A skid section C is pivoted 45 at its forward end to the intermediate point 15 of the skid section D and rests at its rear end upon the bottom. Similarly a skid section B is pivoted to the intermediate point 16 of the skid section C and rests upon the bottom at its rear end and a skid section A is pivoted to the intermediate point 17 of the skid section B and rests at its rear end upon the bottom.

55 The detailed construction of the skid

section A is disclosed in Fig. 7 in which a pipe P is shown in position in the skid. This section comprises two longitudinal supporting members 18 and 19, a bottom pipe guide 20, and two side guides 21 and 22. The bottom guide 20 is supported on suitable cross-pieces 23 which rest on the supporting members 18 and 19. The side guides 21 and 22 are carried by suitable uprights 24 and 25 secured at the lower ends 60 to the supporting members 18 and 19.

The detailed construction of the skid section B is disclosed in Fig. 6 in which the pipe P is again shown in position. This section consists of heavy longitudinal members 26 and 27 which in themselves act as the side guides for the pipe. Recessed into the inner faces of these longitudinal members 26 and 27 are U-shaped strips 28, to which is secured, at the base of the U, a 70 suitable upper guide 29 to prevent the pipe from escaping from the skid. Secured to the lower faces of the longitudinal members 26 and 27 are suitable cross-pieces 30 carrying the lower pipe guide 31. The skid sections A and B are connected together by pivoting the front end of the section A to the intermediate point of the section B in any suitable manner such as by a pin passing through the longitudinal members 18 75 and 19 of the section A and through suitable depending lugs on the longitudinal members 26 and 27 of the section B.

The detailed construction of the section C is best illustrated in Fig. 5 in which I have 80 again shown the pipe P in position. This section comprises suitable longitudinal members 32 and 33 to which are secured inwardly extending side guides 34 and 35 to hold the pipe against lateral displacement. 85 Secured to the bottom of these longitudinal members 32 and 33 are suitable cross-pieces 36 carrying the bottom guide sleeper 37 to which is secured the bottom guide strip 38. Secured to the top of the longitudinal members 32 and 33 are suitable uprights 39 and 40 supporting at the upper ends cross-pieces 41 between which are secured suitable top guide strips 42. To aid in securing the guide strips 42 to the cross-pieces 41 I may 90 provide reinforcing members such as the splices 43 each secured to the top of a cross-piece 41 and overlapping the ends of the adjacent top guide pieces 42 to which the splice is secured. The means of securing 100 105 110

- the section B to the section C is illustrated in detail in Figs. 2, 3, and 4. Each of the longitudinal members 32 and 33 of the section C has secured to its faces a pair of plates 44 each of which is provided at the lower extending edge with an aperture through which extends a cross-shaft 45 suitably secured to the plates by means of nuts 46. Secured to each face of the longitudinal members 26 and 27 of the section B are suitable depending lugs 47 apertured to receive the cross-shaft or pivot pin 45 to thus pivot the section B to the intermediate point 16 of the section C.
- 15 I have not considered it necessary to illustrate the detailed construction of the skid section D or the means of connection between the section C and the skid section D. This skid section D may be constructed in 20 substantially the same manner as the section C and by spacing the longitudinal members 48 thereof a suitable distance apart the longitudinal members 32 and 33 of the skid C may be accommodated therebetween. It 25 will be understood that this involves merely the lengthening of the cross-pieces 36 and 41 and the widening of the side guides 34 and 35. If such a construction is employed, the pivoted connection between section C and 30 section D will be substantially the same as that between the section B and section C illustrated in Figs. 2, 3, and 4. As an alternative construction I may construct skid section D similar to skid section B to thus 35 fit within the longitudinal members 32 and 33 of the section C, in which case the joint construction will again be substantially identical with that disclosed in Figs. 2, 3, and 4.
- 40 It will be understood that the top and bottom guide members of each section terminate at the point at which the next section is connected so that the various top guide members form a continuous guide for the pipe to 45 the point where the section A begins and the bottom guide members form a continuous guide for the pipe to the extreme tip of the skid A. In some cases it may be desirable to provide a top guide on the section A and in 50 such cases this top guide may be supported in any suitable manner such as by extending the side guide supports 24 and 25 to form U-shaped members similar to the member 28 of section B.
- 55 In order to prevent the deviation angle between adjacent skids from becoming larger than the safe angle of flexibility of the pipe being laid, I find it desirable to connect the bottom or front end of each of 60 the sections D and C to the opposite intermediate point on the section C or B, respectively, by any suitable flexible means, such as a chain 49. If desired, this chain may also be employed to connect the sections B 65 and A in the same manner.

It will be apparent from a consideration of Fig. 1 that as the bottom rises the deviation angles between the skids will automatically decrease and the pipe-laying operation may continue without any alteration in the 70 skid supporting means. Similarly, when the bottom recedes the deviation angles will automatically increase but in such case this increase of angle will be limited by the chains 49 so that again the pipe-laying operation may be continued without any adjustment of the skid supporting means. It will be apparent, then, that my pipe skid operates entirely automatically over uneven bottoms to permit continuous pipe laying 75 without any alteration of the skid or skid support.

It will be understood that the exact number of skid sections employed will depend upon the depth of water in which the pipe is 80 to be laid, upon the maximum angle of deviation permitted, and upon various other factors which need not be stated in detail.

While I have designed my apparatus particularly for use over uneven bottoms and have illustrated and described it in this connection it will be apparent that many features thereof are of utility in any pipe-laying operation. It will also be apparent that my pipe-laying skid possesses advantages 90 other than those specifically pointed out in this specification. It will be understood that the skid herein shown and described is but one form which my invention may assume and that various modifications and 95 changes may be made in the herein disclosed skid without departing from the essential features before mentioned. So far as these changes, modifications, and other advantages are included within the scope of 100 the appended claims, they are, therefore, to be considered as part of my invention.

What I claim is:

1. A launching skid for lowering a line of pipe into position, comprising a plurality of hingedly connected overlapping members and means for connecting each member to the rear end of the member next adjoining it forwardly.
2. A launching skid for lowering a line of pipe into position, comprising a plurality of hingedly connected overlapping members and means for flexibly connecting each member intermediate its ends to the rear end of the member next adjoining it forwardly.
3. A launching skid for lowering a line of pipe into position, comprising a plurality of rigid members, means for hingedly connecting one end of each of said members to an adjoining member intermediate its ends and means for flexibly connecting one end of each of said members with an adjoining member.
4. A launching skid for lowering a line of pipe into position, comprising a plurality

of rigid members, each of said members being hingedly connected at one end to the member next adjoining it forwardly and intermediate its ends to the member next adjoining it to the rear.

5. A launching skid for lowering a line of pipe into position, comprising a plurality of rigid members, each of said members being hingedly connected at its front end to the member next adjoining it forwardly and flexibly connected intermediate its ends with the forward end of said next adjoining member.

10 6. A launching skid for lowering a line

of pipe into position, comprising a plurality 15 of rigid sections having upwardly curved bottoms at their forward ends, a hinged connection at the end of each section connecting with the next adjoining section intermediate its ends, and a chain connecting a 20 point intermediate the ends of each section with the rear end of the next adjoining section forwardly.

In testimony whereof, I have signed my name to this specification this 12th day of 25 September, 1919.

WILLIAM L. CHAPMAN.
